UNITED STATES PATENT OFFICE.

CARL J. E. WAXBOM, OF COLUMBUS, OHIO, ASSIGNOR TO THE JEFFREY MANUFACTURING COMPANY, A CORPORATION OF OHIO.

ELECTRIC CONDUCTOR.

1,169,211.

Specification of Letters Patent. Patented Jan. 25, 1916.

Application filed December 16, 1910, Serial No. 597,640. Renewed June 17, 1915. Serial No. 34,740.

To all whom it may concern:

Be it known that I, CARL J. E. WAXBOM, a citizen of the United States, residing at Columbus, in the county of Franklin and State of Ohio, have invented certain new and useful Improvements in Electric Conductors, of which the following is a specification, reference being had therein to the accompanying drawing.

10 This invention relates to improvements in electric conductors of the class adapted to supply current to electric locomotives or motor cars by means of "trolleys" attached to the locomotive or car and engaging the conductor.

15 My invention is especially adapted for use in coal or other similar mines, and one of its principal objects is to provide a conductor of this class which may be cheaply and quickly put in place, and which may be readily extended in small increments as occasion may require.

20 In the mining of coal by the well known room and pillar method, a main entry is opened, and from this main entry a number of side entries lead off at right angles. With these side entries are connected the "rooms" from which the coal is to be removed. Tracks are ordinarily laid in the 25 main and side entries, and from the side entry tracks, spurs lead off into the various rooms. It has heretofore ordinarily been found impracticable on account of the cost, and on account of the time required to provide 30 trolley wires leading into the rooms to supply current to locomotives on the spur tracks. In fact, in many cases no trolley wires are provided in the side entries. In order to handle cars on the side entry and 35 room tracks, use has been made of either "crab" or "cable reel" locomotives. A crab locomotive is distinguished by a winding drum provided with a cable which may be carried into a room or a side entry and attached to a car. The cable is then wound upon the drum and the car hauled out of the room or side entry. A cable reel locomotive is provided with a reel upon which is wound an electric cable which may be 40 attached to a car. The cable is then wound upon the drum and the car hauled out of the room or side entry. A cable reel locomotive is provided with a reel upon which is wound an electric cable which may be 45 attached to a trolley wire or other source of electric energy in the main entry. As the locomotive advances into a side entry or into a room, the cable is unwound, at the same time supplying current for the locomotive.

When the locomotive returns from a room or side entry, the cable is wound upon the drum, current being still supplied to the locomotive through it.

Locomotives provided with devices such as I have outlined, while satisfactory for many classes of work, have been found nevertheless to be quite expensive not only as to first cost, but also as to maintenance. My invention provides a conductor which can be cheaply and quickly mounted in a mine to serve the function of an ordinary trolley wire and which obviates the necessity of using locomotives provided with a crab or cable reel mechanism.

In carrying out my invention, the side entries of a mine can, if desired, be provided with a trolley wire of the ordinary type, and electric conductors embodying my invention can be used in conjunction with the spur tracks leading into the mine rooms.

75 In the accompanying drawings I have illustrated the forms of my invention which I at present consider preferable, but it will be understood that my invention is not limited to the particular details of construction which I have shown, and that numerous modifications may be made.

80 Figure 1 shows in cross section a side entry and a part of a room connected with the side entry. The room is provided with a spur track and with conductors embodying my invention. A locomotive with two cars is shown entering the room. Fig. 2 is a side view of parts of two conductor sections embodying one form of my invention. Fig. 3 is a plan view partly in cross section of the construction shown in Fig. 2. Fig. 4 is a side elevation showing another form of my invention. Fig. 5 is a plan view partly in cross section of the construction shown in Fig. 4. Fig. 6 is a side elevation showing still another form of my invention. Fig. 7 is a plan view partly in cross section showing the construction shown in Fig. 6. Fig. 8 is an end view showing a modified form of my invention adapted to be directly attached to the roof of a mine. Fig. 9 is a side view of the construction shown in Fig. 8.

85 Referring to the drawing, 1 represents a track laid in a side entry of a mine.

90 2 represents a spur track laid from the track 1 into a mine room.

95 3 represents a trolley wire which may be

of the usual construction and which may be supported in the usual manner. This is mounted in the side entry to supply current to locomotives on the track 1. Such a locomotive is indicated in the drawings by 4 and is shown connected with mine cars 5 and 6, the cars being on the track 2 leading into the room.

7, 7 represent mine posts of the usual type which serve to support the roof of the mine. These are preferably equally spaced at one side of the track 2.

When the form of my invention, illustrated in detail in Figs. 2 and 3, is used, hol- 15 low cylindrical insulators 8, 8 are secured to the posts in vertical positions, preferably two on each. One convenient means for mounting the insulators is to provide them with circumferential grooves 9, 9, and to 20 provide staples 10, 10 which may be driven into the posts and embrace the insulators at the grooves. Conductor bars 11, 11 are provided of suitable length to reach from one post to the next. These bars are, for the 25 sake of rigidity and cheapness, preferably formed of iron or steel. Each end of each bar is doubled back upon itself as shown in the drawings, and then bent vertically upward. The upward bent ends are adapt- 30 ed to extend through the central apertures of adjacent insulators 8, 8 and are provided with threads upon which are screwed nuts 12, 12, which serve to hold the bars or sections in place. The adjacent bends or necks 35 of adjacent sections may be electrically connected by being wrapped with a conductor wire as shown at 13.

Connection may be made between the trolley wire of the side entry and the series of 40 conductor sections in the room by means of a special conductor bar or section, such as is indicated in Fig. 1 by 11^a. If preferred, however, connection may be made to the conductor sections in the room independently by means of a separate conductor, such as is shown in Figs. 2 and 3, and indicated by 14.

It will be understood that as coal is removed from a room and as the face of a 50 room advances, additional posts 7 are put in place from time to time. When a new post is put in position, an additional conductor bar may be added to those already in place, and connected in the manner which 55 has been described. In this way a readily extendible conductor system is provided which permits the locomotives to enter the rooms and handle the cars directly without the use of crab or cable reel devices.

60 Referring to the construction shown in Figs. 4 and 5, 7, 7 represent mine posts. 15, 15 are insulators secured to the posts by means of horizontal lag screws 16, 16. The insulators are provided with vertical slots 65 of suitable shape to permit the reception of

two parallel conductor bar ends. The bars 17, 17 are provided with up-turned ends and these ends extend through the slots in the insulators. If desired, sleeves or bushings 18, 18 may surround the lower parts of 70 the up-turned ends of adjacent sections. These sleeves when used, serve as spacers to keep the main parts of the bars from contact with the insulators. The upper ends of the up-turned portions of the bars are 75 electrically connected by means of a wrapping of conductor wire 19. This wrapping serves the double function of providing electrical connections between adjacent bars, and also of holding the bars in place.

Referring to Figs. 6 and 7, 7 represents a mine post, as before. 20 is a circumferentially grooved insulator secured to a post by means of a horizontal lag screw 21. 22, 22 are conductor bars having their adjacent 80 up-turned portions bent in circular arcs to conform to and engage with a suitable circumferential groove in the insulator 20. The upper ends of the up-turned portions are bent back to form hooks 23. These hooks 85 are connected by means of a wrapping of conductor wire 24. A similar wrapping of conductor wire 25 is provided below the grooved part of the up-turned portions.

In Figs. 8 and 9 I have shown a form of 90 my invention which is adapted to be directly connected with a mine roof and which may be mounted entirely independently of the posts. 26 represents a vertical pin which is semi-circular in cross section, and which is 95 provided with teeth 27. 28 is a second pin similar to 26, but without teeth. In securing the pins in place, 26 is first inserted in a suitable hole drilled in the roof of the mine, and then 28 is driven into the hole. The engagement of the pin 28 with the pin 26 forces the teeth 27 into engagement with the side of the hole and both pins are thus firmly locked in place. The lower end of the pin 26 is provided with a horizontal part 100 105 110 115 120 125 130 135 140 145 150 155 160 165 170 175 180 185 190 195 200 205 210 215 220 225 230 235 240 245 250 255 260 265 - tions each consisting of a single rod substantially inflexible under its own weight, fixed but readily disconnectible means for forming electrical connections directly between 5 the adjacent ends of adjacent sections, and means for rigidly supporting the said sections solely at their ends, the said supporting means being adapted to permit the sections to be readily attached thereto or detached therefrom, substantially as set forth. 10
3. In a conductor of the class described, the combination of a series of conductor sections each consisting of a single metallic rod substantially inflexible under its own weight 15 and each having its end parts bent at angles to the main part, means for electrically connecting the said end parts, and devices for supporting the sections by means of the said end parts, substantially as set forth. 20
4. In a conductor of the class described, the combination of a series of conductor sections each substantially inflexible under its own weight and each having its end parts bent at angles to the main part, devices for 25 supporting the sections by means of the said end parts, and means for electrically connecting the adjacent end parts of each two adjacent sections comprising a flexible conductor wire wrapped about the said adjacent end parts, substantially as set forth. 30
5. In a conductor of the class described, the combination of a series of alined conductor sections each substantially inflexible un-
- der its own weight and each having its end parts bent at angles to the main part, devices 35 for supporting the sections by means of the said end parts, and means for electrically connecting adjacent sections comprising a flexible conductor wire engaging with each of them, substantially as set forth. 40
6. In a conductor of the class described, the combination of a series of conductor sections each having its end parts bent at angles to the main part, devices for supporting the sections by means of the said end parts, and means for electrically connecting the adjacent end parts of each two adjacent sections comprising a flexible conductor wire wrapped about the said adjacent end parts, substantially as set forth. 45
7. In a conductor of the class described, the combination of a series of alined conductor sections each having its end parts bent at angles to the main part, devices for supporting the sections by means of the said end parts, and means for electrically connecting adjacent sections comprising a flexible conductor wire engaging with each of them, substantially as set forth. 50

In testimony whereof I affix my signature, 60
in presence of two witnesses.

CARL J. E. WAXBOM.

Witnesses:

DUDLEY T. FISHER,
ETHEL ELLIS.
